UNITED STATES PATENT OFFICE.

JACOB PATTERSON, OF MONROE, NEW YORK.

IMPROVEMENT IN PISTONS FOR PUMPS.

Specification forming part of Letters Patent No. 36,912, dated November 11, 1862.

To all whom it may concern:

Be it known that I, JACOB PATTERSON, of Monroe, in the county of Orange and State of New York, have invented a new and useful Improvement in Pistons for Pumps; and I do hereby declare that the following is a full, clear, and exact description of the same, reference being had to the accompanying drawings, making a part of this specification, in which—

Figure 1 is a vertical section of my invention, taken in the line $x-x$, Fig. 2; Fig. 2, a horizontal section of the same, taken in the line $y-y$, Fig. 1.

Similar letters of reference indicate corresponding parts in the two figures.

This invention relates to an improvement in the packing of the piston, whereby the latter may always be kept in proper working order.

To enable those skilled in the art to fully understand and construct my invention, I will proceed to describe it.

A represents a hollow cylinder, which may be of wood or metal, and provided with a shoulder, a , near its upper part.

B is a collar or sleeve, which is fitted on the cylinder A below the shoulder a . This collar or sleeve is allowed to slide freely on the cylinder A, and its lower end is provided with arms b , and a central ring, c , through which a rod, C, passes, the lower end of the latter having a screw-thread, d , on it, on which a nut, D, is fitted, as shown clearly in Fig. 1. The rod C passes up through the cylinder A, and has a shoulder, e , upon it, underneath which a circular perforated plate, f , is placed,

said plate serving as a guard or stop for a valve, E, the seat of which is formed by the upper edge of the cylinder A. The valve E may also be of india-rubber.

F represents a packing of annular form, and fitted on the cylinder A between the shoulder a and the collar or sleeve B. This packing is of india-rubber, and is made to fit snugly in the pump-cylinder, so as to produce the necessary vacuum in the pump-cylinder as the cylinder A is raised.

The cylinder A may be termed the "box" of the piston, and at any time when the packing F becomes worn by use it may be expanded by turning the nut D, and thereby forcing upward the collar or sleeve B, the packing F being compressed between the shoulder a and the collar or sleeve. Thus by this very simple arrangement the packing may always be kept in perfect working order by simply turning or screwing up the nut D whenever the packing is worn so as to work loosely in the pump-cylinder. The piston is attached to the rod C, and the invention is applicable to all pumps.

Having thus described my invention, what I claim as new, and desire to secure by Letters Patent, is—

The combination of the two open adjustable cylinders or sleeves A B, open ring c , and packing F with the rod C, valve E, perforated plate f , and nut D, all in the manner herein shown and described.

JACOB PATTERSON.
